UNITED STATES PATENT OFFICE.

ALVIN C. LARSON, OF ROCKFORD, ILLINOIS, AND CHARLES JOHAN OLOFSON, OF DETROIT, MICHIGAN.

HAT-CONFORMATOR.

1,175,776.

Specification of Letters Patent. Patented Mar. 14, 1916.

Application filed August 12, 1915. Serial No. 45,146.

To all whom it may concern:

Be it known that we, ALVIN C. LARSON and CHARLES J. OLOFSON, citizens of the United States, and residents of Rockford, 5 in the county of Winnebago and State of Illinois, and Detroit, in the county of Wayne and State of Michigan, respectively, have invented an Improvement in Hat-Conformators, of which the following is a 10 specification.

This invention is an improvement in hat conformators, and has particular reference to a device which may be automatically fitted to the head and the hat subsequently 15 mounted thereon and shaped to conform to the head of the person to be fitted.

An object of the invention is to provide a plurality of radially adjustable shaping bars or ribs which are mounted on a base 20 in a novel manner and adapted to be adjusted to a size approximating that of the head to be fitted whereupon the device is placed in position and the bars are automatically adjusted to accurately determine 25 the shape of the head.

Another object is the provision of a novel form of locking device which is operated to lock the bars in adjusted position so that the exact shape of the head may be retained 30 whereby the hat may be placed over said bars and made to conform to said shape.

A further object is the provision of a device of this character which is simple in 35 construction, easy to manufacture, durable, light, and effective in carrying out the purpose for which it is designed.

The inventive idea involved is capable of receiving a variety of mechanical expressions, one of which, for the purpose of illustrating the invention, is shown in the accompanying drawings, in which—

Figure 1 is a vertical longitudinal sectional view of the conformator constructed 45 in accordance with the invention. Fig. 2 is a section on the line 2—2 of Fig. 1. Fig. 3 is a top plan view of the device. Fig. 4 is a section on the line 4—4 of Fig. 2. Fig. 5 is a detail side elevation of one of the shaping bars used in connection with the invention. Fig. 6 is a fragmentary section on the line 6—6 of Fig. 2.

Referring to the drawings the numeral 10 indicates the base of the device which is 55 preferably oval in shape and enlarged as

indicated at 11 around its periphery, as best shown in Fig. 1. The top of the base 10 is provided in the enlarged portion 11 with a plurality of radially extending slots 12 in which are slidably mounted guides 13 the 60 outer ends of which engage the vertically arranged shaping bars or ribs 14 having at their lower ends the rubber tips 15 adapted for engagement with the head. Certain of the bars 14 carry vertically adjustable hat 65 supports 16 which are mounted in brackets 17 secured therein by means of set screws 18. The enlarged portion 11 of the base is also provided with a plurality of radial openings 19 adapted to receive therein the 70 pins 20 carried by the bar 14 whereby the latter will at all times be maintained in a vertical position when the same are being adjusted back and forth. An endless coil 75 spring 21 is mounted in the bars 14 contiguous to the point of engagement of the guides 13 therewith, said spring being adapted to normally retain the guides 13 in their innermost positions.

Centrally mounted in the base 10 is a vertical shaft 22 having rotatable thereabout a large pulley 23. This pulley is provided at its periphery with a plurality of small angular slots 24 which are adapted to receive one end of a small wire or other flexible element 25, said end being secured to the pulley by means of a set screw 26. The other ends of the wires 25 are secured to every other guide 13 and intermediate its ends said wire passes over a pulley 27 which is mounted 85 between the guide to which said wire is secured and the next adjacent guide on one side thereof. When the pulley 23 is rotated, in a manner which will appear in the course 90 of this description, in a clockwise direction, as shown in Fig. 2, a pull will be exerted upon the wires 25 which will slide the guides 13 outwardly and consequently adjust the bars 14 in a similar direction against the tension of the spring 21. A small pulley 95 28 is mounted upon the inner end of each of the guides 13 and is adapted to be contacted by the wire 25 so that the same will be guided when the bars are being adjusted.

A locking device is employed in connection with the invention for retaining the bars in position after the same have been fitted to the head and comprises a large disk 29 which is mounted upon the shaft 22 and provided at its periphery with a depending 100 105 110

flange 30 having an annular pad 31 abutting thereagainst. This disk 29 is supported by means of a sleeve 32 mounted upon the shaft 22 and having an annular flange 33 at the bottom thereof in which are mounted 5 the upper ends of guide pins 34, the lower ends of which are slidable in openings 35 formed in the pulley 23. The sleeve 32 has secured thereto another sleeve 36 which 10 also surrounds the shaft 22 and is provided at its upper end with a plurality of radial handles 37 whereby the sleeves 32 and 36 may be rotated and through the medium of the pins 34 transmit a similar motion 15 to the pulley 23. The disk 29 together with the pad 31 is vertically adjustable and adapted to be normally retained in its uppermost position by means of a spring 38 coiled about the shaft 22 and engages the 20 base 10 and the lower end of the sleeve 32. Springs 39 are also employed for this purpose and are wound about guide pins 40 mounted upon the base 10 and engaging openings formed in the disk 29. A locking 25 lever 41 is pivoted to the upper end of the shaft 22 and has an inner cam surface 42 which is adapted to force the sleeve 36 and the parts connected thereto downwardly when said lever is moved to the substantially 30 horizontal position. The operation of this lever will force the disk or plate 29 downwardly and cause the pad 31 to contact with the sharp projections 43 extending upwardly from the small pulleys 28. This 35 will prevent any further radial movement of the guides 13 until the lever 41 is again moved to its original vertical position whereupon the springs 38 and 39 will force the disk 29 upwardly. As shown in Fig. 4 40 a grip 44 is secured to the enlarged portion 11 of the base whereby the device may be readily handled. A vertically adjustable head rest 45 is threaded in the lower end of the shaft 22 whereby the device may be 45 made to assume a proper position upon the head to be fitted.

In practice, the bars 14 are first adjusted outwardly to a position which will be slightly larger than the head to be fitted. 50 The device is then placed upon the head and the coil spring 21 will move the bars 14 inwardly until the tips 15 snugly engage the head whereupon the lever 41 is actuated to lock the guides 13 against further movement. The hat to be shaped may then be placed over the upper ends of the bars 14 and treated in any preferred manner, such as by steaming, until the hat conforms exactly with the shape indicated by the 55 bars 14.

What is claimed is:—

1. A hat conformator comprising a base, a plurality of radially arranged guides 65 slidably mounted on said base, vertically arranged bars coöperating with said guides,

means engaging said bars for normally retaining the same and said guides in innermost positions, a shaft carried by said base, a pulley rotatable about said shaft, a plurality of flexible elements secured at one end 70 to said pulley and at the other end to said guides, means for rotating said pulley to adjust said guides and bars outwardly, and vertically adjustable means mounted upon said shaft for retaining said guides and bars 75 in adjusted position.

2. A hat conformator comprising a base, a plurality of radially arranged guides 80 slidably mounted on said base, vertically arranged bars coöperating with said guides, means engaging said bars for normally retaining the same and said guides in innermost positions, a shaft carried by said base, a pulley rotatable about said shaft, a plurality of flexible elements secured at one 85 end to said pulley and at the other end to said guides, means for rotating said pulley to adjust said guides and bars outwardly, vertically adjustable means mounted upon said shaft for retaining said guides and bars 90 in adjusted position, and vertically adjustable hat supports carried by certain of said bars.

3. A hat conformator comprising a base, a plurality of radially arranged guides 95 slidably mounted on said base, vertically arranged bars coöperating with said guides, means engaging said bars for normally retaining the same and said guides in innermost positions, a shaft carried by said base, a pulley rotatable about said shaft, a plurality of flexible elements secured at one end to said pulley and at the other end to said guides, and means for rotating said pulley to adjust said guides and bars 100 outwardly.

4. A hat conformator comprising a base, radially arranged guides adjustably mounted on said base, bars associated with said guides, an element mounted on said base 110 and rotatable relative thereto, and flexible connections between certain of said guides and said rotatable element for adjusting the former outwardly.

5. A hat conformator comprising a base, radially arranged guides adjustably mounted on said base, bars associated with said guides, an element mounted on said base and rotatable relative thereto, flexible connections between certain of said guides and said rotatable element for adjusting the former outwardly, and means mounted on said base and adjustable relative thereto for locking said guides in adjusted position. 115

6. A hat conformator comprising a base, radially arranged guides adjustably mounted on said base, bars associated with said guides, an element mounted on said base and rotatable relative thereto, flexible connections between certain of said guides and 120

said rotatable element for adjusting the former outwardly, and depressible means for locking said guides in adjusted position.

7. A hat conformator comprising a base, 5 radially arranged guides adjustably mounted on said base, bars associated with said guides, an element mounted on said base and rotatable relative thereto, flexible connections between certain of said guides and 10 said rotatable element for adjusting the former outwardly, depressible means for locking said guides in adjusted position, and means for returning the last-named means to normal position.
- 15 8. A hat conformator comprising a plurality of radially adjustable head engaging and hat receiving members, guides for adjusting said members, flexible elements connected to said guides, and a rotatable element 20 connected to said flexible elements and adapted to actuate the same to adjust said guides.

9. A hat conformator comprising a plurality of radially adjustable head engaging 25 and hat receiving members, guides for adjusting said members, flexible elements connected to said guides, a rotatable element connected to said flexible elements and adapted to actuate the same to adjust said 30 guides, and means for locking said guides in adjusted position.

10. A hat conformator comprising a plurality of radially adjustable head engaging and hat receiving members, guides for adjusting said members, flexible elements connected to said guides, a rotatable element connected to said flexible elements and adapted to actuate the same to adjust said 35 guides, and means adjustable relative to 40 said rotatable element for locking said guides in adjusted position.

11. A hat conformator comprising a plurality of radially adjustable head engaging and hat receiving members, guides for adjusting said members, flexible elements connected to said guides, a rotatable element connected to said flexible elements and adapted to actuate the same to adjust said 45 guides, and depressible means for locking 50 said elements in adjusted position.

12. A hat conformator comprising a base, a plurality of radially adjustable head engaging and hat receiving members associated therewith, and cam operated means 55 for locking said members in adjusted positions.

13. A hat conformator comprising a base, 60 a plurality of radially adjustable head engaging and hat receiving members associated with said base, guides for said members, projections carried by said guides, a locking device adjustable relative to said base and including a pad adapted for en-

gagement with said projection to lock said head engaging and hat receiving members 65 in adjusted position, and a cam lever for operating said locking device.

14. A hat conformator comprising a base, a plurality of radially adjustable head engaging and hat receiving members associated therewith, 70 radially movable guides for said members, and cam operated means movable transversely of said guides and adapted to engage the same for locking said members in adjusted positions. 75

15. A hat conformator comprising a plurality of radially adjustable head engaging and hat receiving members, guides for adjusting said members, flexible elements connected to said guides, and a rotatable 80 element connected to said flexible elements and adapted to actuate the same to adjust said guides.

16. A hat conformator comprising a plurality of adjustable head engaging and hat 85 receiving members, a rotatable element, and connections between said rotatable element and said adjustable members operated by the former to adjust the latter.

17. A hat conformator comprising a plurality of adjustable head engaging and hat receiving members, a rotatable element, connections between said rotatable element and said adjustable members operated by the former to adjust the latter, and a locking 95 device for releasably retaining said adjustable members in adjusted positions. 90

18. A hat conformator comprising a plurality of adjustable head engaging and hat receiving members, a rotatable element, connections between said rotatable element and said adjustable members operated by the former to adjust the latter, a locking device for releasably retaining said adjustable 100 members in adjusted positions, and means 105 for returning said device to unlocking position when the same is released.

19. A hat conformator comprising a plurality of adjustable head engaging and hat receiving members, a rotatable element, connections between said rotatable element and said adjustable members operated by the former to adjust the latter, a locking device for releasably retaining said adjustable 110 members in adjusted positions, and guiding 115 means for said locking device engaging said rotatable element.
